CLAIM

The ornamental design for a housing for a ceiling array microphone, as shown and described.

DESCRIPTION

FIG. 1 is a bottom perspective view of a housing for a ceiling array microphone;

FIG. 2 is a top perspective view thereof;

FIG. 3 is a side elevation view thereof, the opposite side elevation view and the two end elevation views being identical thereto;

FIG. 4 is a top plan view thereof;

FIG. 5 is a bottom plan view thereof;

FIG. 6 is a bottom perspective view thereof, shown in an environment of use;

FIG. 7 is a top perspective view thereof, shown in an environment of use;

FIG. 8 is a side elevation view thereof, shown in an environment of use, the opposite side elevation view and two end elevation views being identical thereto;

FIG. 9 is a top plan view thereof, shown in an environment of use; and,

FIG. 10 is a bottom plan view thereof, shown in an environment of use.

The broken lines in FIGS. 1, 2, 4 and 5 show portions of the housing for a ceiling array microphone that form no part of the claimed design. The broken lines illustrating the ceiling in FIGS. 6–10 are environment, while the remaining broken lines in FIGS. 6–10 illustrate portions of the housing for a ceiling array microphone that form no part of the claimed design.
